UNITED STATES PATENT OFFICE.

MARIE PERILLAT, OF NEW YORK, N. Y., ASSIGNOR TO YE LADY'S OUTFITTERIE, A COPARTNERSHIP COMPOSED OF SIDNEY H. BURNS AND CHARLES D. PERILLAT, BOTH OF NEW YORK, N. Y.

BUST-REDUCER BRASSIÈRE.

1,156,808.

Specification of Letters Patent.

Patented Oct. 12, 1915.

Application filed May 24, 1913. Serial No. 769,583.

To all whom it may concern:

Be it known that I, MARIE PERILLAT, a citizen of France, and a resident of the city of New York, borough of Manhattan, in the county and State of New York, have invented a new and Improved Bust-Reducer Brassière, of which the following is a full, clear, and exact description.

This invention relates to ladies' apparel, and has particular reference to means for adding to the comfort and appearance with respect especially to bust forms.

Among the special objects of this invention is to provide a device having a neat appearance which serves to reduce or support a woman's bust in accordance with the demands of the present modes of dress.

More specifically stated, one of the objects of the invention is to provide a device for use by large women which will serve to add to the graceful appearance of their busts as well as adding to their comfort.

Another object of the invention is to provide a brassière including a pair of side back pieces made of rigid material to prevent flesh bulging and corset lines, thus providing a smooth back foundation for gowns.

A further object of the invention is to form in a device of the character indicated a center back piece made of elastic webbing to provide elasticity, thus preventing wrinkling and displacement of said side back pieces.

A still further object of the invention is to introduce a pair of elastic breast pieces to prevent relaxation, bulging and corset lines and, on the whole, providing a comfortable and hygienic support and a smooth and shapely gown foundation that is self adjustable.

The foregoing and other objects of the invention will hereinafter be more fully described and claimed and illustrated in the drawings forming a part of this specification in which like characters of reference indicate corresponding parts in all the views, and in which—

Figure 1 is a perspective view of a preferred embodiment of this brassière shown in position at the top of a low-bust corset; Fig. 2 is a back view of the same; Fig. 3 is an elevation showing the inner surface of the device extended; and Fig. 4 is a ver-

tical transverse section on the line 4—4 of Fig. 3.

The device may be made of any suitable materials and the relative sizes and proportions of the parts, as well as the general design or ornamentation thereof, may be varied to a considerable extent without departing from the spirit of the invention herein-after more fully set forth and specifically claimed.

Referring more particularly to the drawings, this brassière includes a pair of side backs 10 connected at their opposing edges 11 by an elastic transversely extending back strap 12. The width of the back strap coincides substantially with the vertical width of the side backs 10, and said elastic strap 12 is permanently connected to said side backs. Each of the side backs is provided with a shoulder strap 13 which extends upwardly and forwardly over the shoulder and provided with a plurality of eyelets 14 at its free end.

At the front of the device I provide a pair of breast pieces 15 of peculiar construction, each of which is made of peculiarly knitted fabric and provided with elastics 15' for extension in one direction only, namely, circumferentially of the wearer. These pieces are knitted or woven over a convex die, thus putting the convexity into the fabric circumferentially instead of vertically or transversely, whereby they are given a convex form and are prevented from stretching in a vertical direction; that is to say, they are so formed as to be much wider vertically at their centers than they are at their ends. The pieces 15 are secured permanently at their outer ends at 16 to the ends of the side backs remote from the back, and at their front or adjacent ends they are provided with means of any suitable nature for securing them together at the front of the person, as shown in Fig. 1. The securing means illustrated comprises a set of hooks 17 carried by one member and eyes 18 carried by the other member.

As shown in Figs. 3 and 4 each of the pieces 15 is provided with a vertically arranged rib 19 stitched at its ends preferably upon the inner surface of said piece substantially midway between its ends. This

rib serves to maintain the piece distended vertically which adds to the convenience as well as the appearance of the device when in use. At the upper edge and preferably adjacent the upper end of each of the ribs 19 I provide a tab 20 having a hook 21 for cooperation with the eyelets 14 of the shoulder straps. At 22 I show one or more casings extending downwardly and diagonally along the side backs 10 substantially from one end to the other, and in each of said casings I provide a stiffener 23 which may occupy any desired portion of the length of its casing, preferably, however, extending only partially from one end to the other, as shown in Fig. 3. The purpose of these stiffeners is to assist in preserving the most desirable form of a fleshy person, but it is to be noted in this connection that by providing for the adjustment of such stiffness along the casings, they may be placed wherever found most desirable for their purpose according to the individual. I also prefer to employ a downwardly extending tab 24 secured at one end at 25 to the front end of one of the breast piece fasteners, said tab being provided with an eyelet 26 whereby the same may be secured in place by attachment to a corset stay or may be secured in any other suitable way. These devices are made in sizes. A woman having a forty inch bust, for instance, by the use of a number 38 brassière made in accordance with this invention, may apply and wear the same with absolute comfort with a much neater appearance than would be possible without the same. The elasticity of the back strap 12 and the breast pieces, together with the adjustment provided along the eyelets 14, will insure absolute comfort

in connection with the added appearance 40 to the figure due to the application of the device as above set forth. It is to be noted, furthermore, that this device is adapted especially for use in connection with the low-bust corsets now commonly worn, and hence 45 I provide means to meet the demands of the smartest appearing women with respect to the neat appearance which depends so largely upon the proper corset and brassière. 50

Having thus described my invention, I claim as new and desire to secure by Letters Patent:

In a brassière of the character set forth, the combination of a pair of side backs, an elastic strap connecting the same together at the back, each of the side backs being provided with one or more diagonally extending casings extending from one end to the other, a stiffener in each of said casings, a breast piece secured at one end to the outer end of each of the side backs, said piece being formed convex and wider at the middle than at its ends and provided with elastics extending from one end to the other, means 55 connected to each of the breast pieces maintaining it substantially in definite form vertically, means to secure the free ends of the breast pieces together in the front, and straps and tabs serving to maintain the brassière in definite position vertically. 65

In testimony whereof I have signed my name to this specification in the presence of two subscribing witnesses.

MARIE PERILLAT.
